SURGICAL FACE MASK

William H. Bird, Somerset, N.J., assignor to Johnson & Johnson, a corporation of New Jersey

Filed Oct. 8, 1968, Ser. No. 13,888

Term of patent 14 years

Int. Cl. D24—02, 99

U.S. Cl. D83—1

FIG. 1 is a front plan view of a surgical mask embodying my new design;

FIG. 2 is an enlarged fragmentary front plan view of the face portion of the mask showing my new design in greater detail with the straps broken away;

FIG. 3 is an enlarged fragmentary back plan view showing the design of the back portion of the mask with the straps broken away;

FIG. 4 is an enlarged fragmentary cross sectional view of the mask taken along line 4—4 of FIG. 2.

The characteristic features of the surgical face mask design reside in the unique pattern formed by the arrangement of the folds and straps.

I claim:

The ornamental design for a surgical face mask, substantially as shown and described.
